TURBULENCE RECTIFIER

Roy S. McKeever, Tulsa, Okla., assignor to Smith
Separator Corporation, Tulsa, Okla., a corpora-
tion of Oklahoma

Application June 7, 1937, Serial No. 146,931

4 Claims. (Cl. 183—2.7)

This invention relates to a turbulence rectifier for controlling fluid passing through a pipe or the like, and while the device has been designed specifically for use with oil and gas separators, it will be apparent to those skilled in the art that it has numerous other applications.

The ordinary work of an oil and gas separator where there is a better ratio between oil and gas is a simple matter for complete separation, but with an excessive gas volume and a small amount of oil, the gas has a tendency to carry over oil which is blown to the air and lost. Conventional separators having ordinary pipes for introducing the mixture of oil and gas into the separating chamber are liable to be instrumental in the loss of oil where the amount of gas is greatly in excess of the amount of oil.

It is the primary purpose of my invention to provide a separator inlet means which will check turbulence; assist in separating the oil from the gas and prevent the loss of oil.

With the foregoing object outlined and with other objects in view which will appear as the description proceeds, the invention consists in the novel features hereinafter described in detail, illustrated in the accompanying drawing, and more particularly pointed out in the appended claims.

In the drawing:

Fig. 1 is a side elevation of an oil and gas separator provided with my improved inlet means or turbulence rectifier.

Fig. 2 is an enlarged sectional view of the rectifier taken on the line 2—2 of Fig. 1.

Fig. 3 is a transverse vertical sectional view taken on the line 3—3 of Fig. 1.

Fig. 4 is a view similar to Fig. 2 but illustrating a modification.

Referring to the drawing, 5 designates an oil and gas separator having a gas outlet 6 and an oil outlet 7. My improved intake means or turbulence rectifier is shown at 8. It preferably consists of an elongated hollow or tubular member 9 preferably of cylindrical shape and having gradually contracted tapered end portions 10 which terminate in cylindrical extremities 11 that are restricted in internal diameter in comparison with the internal diameter of the portion 9.

Vanes or partitions 12 are arranged in the tubular member and they are preferably radially disposed, and act to divide fluid flowing through the device into a number of streams, preferably four. Each vane or partition preferably extends from one contracted portion of the tubular member to the other and each vane extends diametrically

across the interior of the tubular member as clearly shown in the drawing.

An obstruction 13 of ellipsoidal shape intersects the vanes and is supported thereby in a position centrally of the tubular member 9 and about mid-way between the ends of the vanes. Obviously, the member 13 restricts the flow of fluid through the tubular member and causes the fluid to travel through the tubular member between that member and the obstruction. 10

Instead of making the member 13 of ellipsoidal shape, it may be spherical as shown at 14 in Fig. 4. The members 13 and 14 are shown as hollow, but of course, they may be made solid if desired.

In operation, the mixture of oil and gas enters the device at A and is immediately expanded in the portion B, or rather the velocity is decreased by the increased area of the medial portion of the device. The mixture is then split into a plurality of streams which travel forwardly about 20 the ellipsoid or sphere, and then the reverse action takes place as the mixture passes beyond the end of the ellipsoid or sphere, until the velocity of the fluid passing through C into the oil and gas separator is the same as upon entering at A. 25

Expansion immediately takes place when the mixture enters the separator on account of the enlarged area in comparison with the area of the port C. My structure has the effect of eliminating the turbulence and the liquids entrained with the gas are deposited upon the surfaces of the vanes and the ellipsoid or sphere. Consequently, the liquids pass into the separator in a partly separated condition.

A foamy and emulsified fluid consisting of a liquid and gas and having a turbulent motion, upon entering the port A will immediately expand and reduce its velocity which will allow settling and time for breaking up of emulsified or foamy particles or bubbles. Then the course of the 40 stream will be straightened by entering the passageways formed by the vanes and passing on to the ellipsoid or sphere, as will be clear from Fig. 2. The pressure created on the fluid by the smooth surface of the ellipsoid or sphere causes 45 the emulsified or foamy particles to further separate and break down into a more dense liquid which separates from the free gas.

From the foregoing, it will be understood that my improved turbulence rectifier transforms a turbulent and heterogeneous mass of liquid and gas entering at A into smooth flowing streams from which the liquid is at least partially removed by gathering on the vanes and ellipsoid or sphere. 50 55

While I have disclosed preferred embodiments of the invention shown in use with an oil and gas separator, it will be manifest to those skilled in the art that many other embodiments may be made and that the device may be employed wherever it has utility. It should therefore be understood that I intend to claim all inherent novelty as expressed in the appended claims.

What I claim and desire to secure by Letters 10 Patent is:

1. A turbulence rectifier comprising a tubular member having a cylindrical bore and end portions of restricted area in comparison with said bore, an obstruction arranged in the medial portion of the tubular member and of less diameter than the internal diameter of the medial portion of the member, said obstruction having substantially hemi-spherical opposite portions, and vanes arranged in the bore extending from one end portion to the other and forming a plurality of longitudinal 15 passageways in the tubular member which are obstructed by said obstruction, the area between the medial portion of the obstruction and the bore being equal to either of the restricted end portions of the tubular member.

2. A turbulence rectifier comprising a tubular member having a cylindrical bore and end portions of restricted area in comparison with said bore, an obstruction of substantially ellipsoidal 20 shape arranged in the medial portion of the tubular member and of less diameter than the internal diameter of the medial portion of said member, said obstruction having a cylindrical body and hemi-spherical end portions, and vanes arranged in the medial portion of the tubular member extending from one end portion to the other and forming a plurality of longitudinal 25 passageways in the tubular member which are obstructed by said obstruction, the area between the medial portion of the obstruction and the bore being equal to either of the restricted end portions of the tubular member.

3. A turbulence rectifier comprising a tubular member having a cylindrical bore and end por-

tions of restricted area in comparison with said bore, an obstruction of substantially ellipsoidal shape arranged in the medial portion of the tubular member and of less diameter than the internal diameter of the medial portion of said member, said obstruction having a cylindrical body and hemi-spherical end portions, and vanes arranged in the medial portion of the tubular member extending from one end portion to the other and forming a plurality of longitudinal 10 passageways in the tubular member which are obstructed by said obstruction, the area between the medial portion of the obstruction and the bore being equal to either of the restricted end portions of the tubular member, said vanes intersecting one another between said obstruction and the restricted end portions of the tubular member.

4. The combination with an upstanding oil and gas separator tank having an upper gas outlet 15 and a lower liquid outlet, of means for conveying a mixture of oil and gas to and through the medial portion of the wall of said tank arranged at a point between said outlets, said means comprising a horizontally disposed tubular member 20 arranged in close proximity to but exteriorly of said tank and having a cylindrical bore and end portions of restricted area in comparison with said bore, an obstruction arranged in the medial portion of the tubular member and having a circular outer surface of less diameter than the bore and equally spaced from the surface of the latter, said obstruction having substantially hemi-spherical opposite portions facing the restricted 25 end portions of the tubular member, the area between the medial portion of the obstruction and the bore being equal to either of the restricted end portions of the tubular member, and vanes arranged in the bore, extending from one of said restricted end portions to the other and forming a plurality of equal passageways in the 30 tubular member which are obstructed by said obstructions.

ROY S. MCKEEVER.
